COMBINED STAND AND ATTACHMENT FOR
REFUSE BAG OR SIMILAR ARTICLE

Richard A. Kallstrom, 4531 N. Merrimac Ave.,
Chicago, Ill.

Filed June 4, 1958, Ser. No. 51,204

Term of patent 14 years

(Cl. D58—26)

Fig. 1 is a perspective view of a combined stand and attachment for refuse bags showing my new design with the cover in open position;

Fig. 2 is a side elevational view thereof with the cover in closed position;

Fig. 3 is a front elevational view of Fig. 2; and

Fig. 4 is a top plan view of Fig. 2.

The dominant features of my design reside in the portions shown in full lines. The bag is shown in broken lines for illustrative purposes only.

I claim:

The ornamental design for a combined stand and attachment for refuse bag or similar article, substantially as shown and described.
